THERMAL RESPONSIVE DEVICE

Russell A. Gougeon, Ecorse, Mich.

Application January 8, 1942, Serial No. 425,996

2 Claims. (Cl. 297—8)

My invention relates to a new and useful improvement in a thermal responsive actuating member primarily adapted for use with cooking utensils as a means for automatically actuating a gas valve or the like upon the rising of liquid being boiled to a certain temperature so that the liquid may be subjected to just enough heat to maintain it at a boiling point.

Another object of the invention is the provision of a mechanism of this class so arranged that a portion thereof may be submerged in liquid to be boiled so as to be affected directly by the temperature of the liquid being boiled.

Other objects will appear hereinafter.

It is recognized that various modifications and changes may be made in the detail of structure illustrated without departing from the spirit of the invention and it is intended that such variations shall be embraced within the scope of the claims forming a part hereof.

Forming a part of this specification is a drawing in which:

Fig. 1 is a central, vertical sectional view of the invention with parts broken away and showing it applied.

Fig. 2 is an enlarged central sectional view of the valve mechanism.

Fig. 3 is a sectional view taken on line 3—3 of Fig. 1.

Fig. 4 is a fragmentary sectional view of a slightly modified form of the invention.

In the drawing I have illustrated a liquid receptacle 9 positioned over a gas burner 10 the liquid level being indicated by the line 11. A valve housing 12 is connected in the usual manner to the gas supply pipe 13 and in this housing 12 is the usual control valve 14 whereby the gas may be turned on and off, this valve controlling the flow of gas through the passage 15. Formed in the housing 12 is a radial cavity or passage 16 communicating with which are passages 17 and 18 which communicate with the passage 19 in the nipple 20. Extending upwardly from the housing 12 is a nipple 21. Slidably mounted in this passage 16 in the nipple 21 is a valve-forming plunger or piston 22 which is connected to the threaded end 23 of a wire 23'. This wire is of the flexible type and extends through the sheathing 24. A nut 25 is threaded on the threaded portion 23 of the 23' wire so that when the threaded portion 23 of the wire is threaded into the piston 22 a predetermined distance the nut 25 may be used as a lock nut. A cap 26 is threaded on the nipple 21 and the sheath 24 projects through the cap of 26.

Positioned in the receptacle 9, so as to be submerged in the liquid contained therein, is a housing 27 having a cover 28 formed thereon, the housing and the cover 28 forming a leak proof connection. Communicating with the interior of the housing 27 and projecting upwardly from the cover 28 is a tube 29 having the enlarged portion 30 upon its upper end. The wire 23' extends into the enlarged tube 30 and is connected to the piston like member 31 which is slidable in the enlarged tube 30. This piston like member 31 is provided on its periphery with a plurality of serrations 32. Secured, at one of its ends to the enlarged tube 30, is a leaf spring 33 having its free end 34 angularly turned to project inwardly through the slot 35 formed in the enlarged tube 30 so as to normally engage the serrated portion of the member 31. A collar or ring 36 is secured to the leaf spring 33 adjacent its free end. This collar or ring 36 embraces the portion 30 and is of larger diameter than the member 31 so that the collar or ring 36 serves as a means for pressing the free end of the leaf spring 33 out of engagement with the serrations 32. Connected to the lower end of the member 31 is a rod 37 which is connected to a heat responsive expandible bellows 38 which is positioned in the housing 27 and filled with suitable liquid. It will be noted that the bellows 38 is of less diameter than the housing 27 and that the enlargement or tube 30 projects above the water level in the receptacle 9 thus the housing 27 is open to the atmosphere and the bellows 38 is surrounded by air.

The operation of the device will now be described:

When it is desired to boil liquid in the receptacle 9 the valve 14 would be open and the gas issuing to the gas burner 10 would be ignited and the mechanism would be in the position shown in Fig. 1. It is recognized that it would not require the application of as much heat to maintain the liquid in boiling condition as it would be to quickly raise the temperature of the liquid to a boiling temperature. Consequently when the gas is first ignited a free flow of the gas through the housing 12 would be permitted. The bellows 38 would be so adjusted that it would expand to a predetermined position when the liquid reaches boiling point. As the bellows expands it would move the rod 37 upwardly and as the member 31 moves upwardly the spring 33 would ride over the succession of serrations thus preventing return movement of the rod 37. The movement of the member 31 would, through

the wire 23', move the piston 22 downwardly into position for covering and closing the end of the passage 17 thus leaving only the passage 18 as an outlet for the gas to the burner 10. This passage 18 may be adjusted by means of a manually operated adjusting valve 42. In this way there is provided a means for automatically shutting off a portion of the gas and controlling the flow of gas to the burner, dependent upon the heat of the liquid in the receptacle 9. When the member 22 has been moved to a position for closing the opening 17 the bellows 38 will not be expanded to its maximum. Should the liquid in the receptacle 9 be boiled away the bellows 38 would further expand and move the valve-forming piston 22 so as to also cover the end of the passage 18, thus completely shutting off the flow of gas to the burner 10. In all of its positions of downward movement the valve-forming piston 22 is secured against reverse movement by the latch mechanism embodying the spring 33 and the serrations 32. This is important, particularly in the event the liquid boils away and the member 26 moves downward to close the passage 18. Were this member 22 permitted to return upon contracting of the bellows 28 it is obvious that the flow of gas to the burner 10 would then be permitted after the burner had gone out. The leaf mechanism therefore is a safety factor which is believed quite desirable and necessary in a device of this kind.

It will be noted that the structure may be mounted in the ordinary valve housing 12 which is commonly used in connection with gas burners without materially increasing the size or weight of the valve structure. Since all of the moving parts of the mechanism in it are enclosed it is believed obvious that interference with its operation through accumulation of foreign material is reduced to a minimum. The structure is also sufficiently light so as to permit its easy manipulation and placement in a receptacle and the wire 23' is sufficiently flexible to permit the storing of the mechanism away around the gas

stove without materially interfering with objects commonly used in connection with a gas stove.

In Fig. 4 I have shown a slight modification of the invention in which the passages 17 and 18 are eliminated and a slot 83 is substituted therefor.

What I claim as new is:

1. In a mechanism of the class described, an expandable heat responsive member; a tube projecting upwardly from said member and opening at its upper end to the atmosphere; a stem connected to said member and slideable in said tube; ratchet teeth on a portion of said stem, said tube having a slot formed therein at said ratchet teeth; a spring carried by said tube and projected at one end through said slot for successively engaging said ratchet teeth upon movement of said stem in one direction for preventing return movement of said stem; and means embracing said tube and attached to said spring for moving said spring out of ratchet teeth engaging position.

2. In a device of the class described, a closed housing adapted for submergence in liquid; an expandable heat responsive member positioned in said housing and spaced at its periphery in spaced relation to the walls of said housing; a tube communicating with the interior of said housing and projecting upwardly therefrom, and open at its upper end, and terminating normally above the liquid level; a stem connected to said expandable member and projecting upwardly and slidably of said tube; said tube having a slot formed therein; ratchet teeth on said stem accessible through said slot; a spring member carried by said tube and projected through said slot for successively engaging said ratchet teeth upon movement of said stem in one direction for preventing return movement of said stem; a means embracing said tube and attached to said spring for moving said spring out of ratchet teeth engaging position.

RUSSELL A. GOUGEON.
